DOOR HINGE

Arthur W. Aspin, Butler, Pa., assignor to American Bantam Car Company, Butler, Pa., a corporation of Pennsylvania

Application September 28, 1945, Serial No. 619,159

4 Claims. (Cl. 16—163)

1

This invention relates to door hinges and more particularly to a hinge for mounting a door at the rear end of a van body to swing laterally from its closed position to a position alongside the van body.

The invention has for its object to provide a hinge for a door that will cause the door to have an opening movement in which it swings through a predetermined angle about one axis and then in the same direction about an axis parallel with but spaced from the first, and a closing movement that is the reverse of the opening movement.

With the above and other objects in view, the invention may be said to comprise the hinge as illustrated in the accompanying drawings, hereinafter described and particularly set forth in the appended claims, together with such variations and modifications thereof as will be apparent to one skilled in the art to which the invention pertains.

Reference should be had to the accompanying drawings forming a part of this specification, in which:

Figure 1 is a fragmentary side elevation of the rear end of a van body showing the wall brackets mounted upon the rear corner of the van body;

Fig. 2 is a fragmentary rear elevation showing the door and hinge members connecting the same to the wall bracket;

Fig. 3 is a section taken on the line indicated at 3—3 in Fig. 1, showing the door in closed position;

Fig. 4 is a section similar to that shown in Fig. 3 showing the door in full open position alongside the van body, and

Fig. 5 is a plan view of the hinge on an enlarged scale.

In the accompanying drawings the invention is shown applied to a van type vehicle body 10 for mounting a door 11 that closes an opening in the rear end of the van body. A wall bracket 12 is formed with a curved base to fit a rear corner of the van body and is attached to the rear corner of the body by suitable means such as screws 13. The bracket 12 has vertically spaced, horizontally disposed outwardly projecting lugs 14 that support a vertical pintle 15 that may be attached to one of the lugs and held against turning movements by suitable means such as a pin 16. The pintle 15 is provided with a conical recess 17 on the side thereof that faces outwardly away from the door opening.

A link 18 has its inner end positioned between the lugs 14 of the hinge bracket and is provided with a bore 19 in which the pintle 15 fits, the link

2

18 being horizontally disposed and mounted to swing laterally on the pintle 15. At its outer end the link 18 is provided with vertically spaced horizontally disposed knuckles 20 and the end portion 5 of the link between the knuckles 20 is provided with a concave arcuate base 21 that conforms to and closely overlies an arcuate exterior surface 22 on a knuckle 23 carried by a door plate 24. The knuckle 23 projects from the plate 24 and fits 10 between the knuckles 20 of the link, the door plate being connected to the link by a vertical pivot pin 25 extending through the knuckles 20 and 23 concentrically with the arcuate surfaces 21 and 22.

15. The door plate 24 is attached to the door 11 by suitable means such as screws 26 and projects laterally beyond the edge of the door 11 for engagement with the outer end of the link 18. The arcuate surface 22 of the knuckle 23 is provided 20 adjacent the outer end thereof with a conical recess 27 that is adapted to register with a longitudinal bore 28 formed in the link 18 and extending from the concave end portion 21 of the link to the transverse bore 19. Inwardly of the 25 recess 27 the knuckle 23 is provided with a shoulder 29 that engages with a shoulder 30 on the link 18 to limit pivotal movement of the plate 24 in one direction with respect to the link 18. When the shoulders 29 and 30 are in engagement the 30 recess 27 is registered with the longitudinal bore 28 of the link, which is movable from the door closing position shown in Fig. 3 to the position shown in Fig. 4 where the bore 28 registers with the recess 17 of the pintle 15. A latch pin 31 is slidably mounted in the bore 28 and has conical ends 32 and 33 forming latch elements that are 35 adapted to fit in the recesses 27 and 17.

When the door 11 is in closed position as shown in Fig. 3, the shoulders 29 and 30 are in engagement and the door plate 24 is locked to the link 18 by engagement of the conical end 32 of the pin 31 with the recess 27 in the knuckle 23. The length of the pin 31 is such that while the end 32 engages in the recess 27 the opposite end 33 bears 45 against the cylindrical exterior surface of the pintle 15 which holds the latch 31 in locking position while the door and the link 18 are swung outwardly about the pintle 15 from the position shown in Fig. 3 to the position where the bore 28 registers with the recess 17. When the link 18 reaches the position shown in Fig. 4 the bore 28 is aligned with the recess 17 of the pintle 15 and pressure against the door 11 in a direction to move it to a position against the side wall of the body 50 will cause the hinge plate 24 to pivot about the

pivot pin 25, the inclined surface of the recess 27 acting as a cam against the tapered end 32 of the latch pin 31 to move the latch pin axially into engagement with the recess 17 of the pintle 15, bringing the end of the conical portion 32 of the pin into engagement with the arcuate surface 22 of the knuckle 23 which holds the pin in locking engagement with the pintle 15 while the door swings to a position alongside the van body.

When the door 11 is swung outwardly from the van body the latch plate 22 swings on the pivot 25 until the shoulder 29 of the door plate engages with the shoulder 30 of the link 18 and the recess 27 is brought into registry with the bore 28 of the link. Further movement of the door toward closed position then causes the latch pin 31 to be cammed into engagement with the recess 27, locking the plate 24 to the link 18 so that the door is held in proper position to swing into the door opening.

It is to be understood that variations and modifications of the specific devices herein shown and described for purposes of illustration, may be made without departing from the spirit of the invention.

What I claim is:

1. A hinge comprising a wall bracket, a door plate, a link pivoted at one end to the bracket and at the other to said door plate, a latch mounted for endwise movement within said link and operable in one extreme position to lock the door plate against turning movement with respect to the link and the other extreme position to lock the link against turning movement with respect to the bracket, and means for automatically shifting said latch from one locking position to the other during swinging movements of said link.

2. A hinge comprising a wall bracket, a door plate, a link connected at its ends to said bracket and plate to pivot about parallel axes, a latch pin slidable longitudinally of the link and interposed between said pivotal axes, said pin being movable from a position locking said plate to said link to a position locking said link to said bracket and cam surfaces on said bracket and plate for shifting said latch pin.

3. A hinge comprising a wall bracket having a fixed pintle provided with a recess in one side

thereof, a link having a transverse bore to receive said pintle and a longitudinal bore opening to said transverse bore and adapted to register with said recess, a door plate connected to the outer end of said link to swing about an axis parallel to the axis of said pintle, said plate having a cylindrical knuckle portion overlying the outer end of said longitudinal bore and provided with a recess adapted to register with said longitudinal bore, and a latch pin slidable in said longitudinal bore, said latch pin being longer than said bore and having tapered ends alternately engageable in said recesses.

4. A hinge comprising a door plate having an outwardly projecting knuckle at one end, the exterior surface of which is arcuate, said knuckle having a shoulder inwardly of said arcuate portion and a substantially conical recess adjacent the shoulder, a link having an end recess to receive said knuckle and pivoted to said plate to swing about an axis concentric with said arcuate surface, said link having a transverse bore at its opposite end parallel to said axis and a longitudinal bore extending from said end recess to said transverse bore and adapted to register with said conical recess, a wall bracket having a pintle fixed thereto and fitting in said transverse bore said pintle having a conical recess adapted to register with said longitudinal bore in one angular position of the link, and a latch pin slidable in said longitudinal bore, said pin having conical ends adapted to fit in said conical recesses, said pin being of a length greater than said longitudinal bore whereby it is held in said knuckle recess by said pintle and in said pintle recess by said knuckle.
